METHOD OF RECOVERING AND INCREASING THE PRODUCTION OF OIL

Filed Oct. 19, 1928

UNITED STATES PATENT OFFICE

PAUL E. WORKMAN, OF DALLAS, TEXAS

METHOD OF RECOVERING AND INCREASING THE PRODUCTION OF OIL

Application filed October 19, 1928. Serial No. 313,458.

This invention relates to a method of recovering and increasing the production of oil, and particularly to the formation within the well of a gas which will combine with the oil and also affect the oil bearing strata.

In this art efforts have been previously made to increase the flow of oil by the use of electrical heating units which in effect cause a distillation of the oil and only affect surrounding strata by increasing the temperature thereof without any material reaction upon the viscosity of the oil or gaseous pressure upon the oil bearing sands to increase the flow therefrom.

The present method seeks to produce a gaseous reagent which will be absorbed by the oil, effect a pressure upon the sands, and also tend to seal water channels leading into the well. For this purpose I introduce an electrode into the natural or mineralized water from the oil bearing strata and by feeding a proper current thereto cause an electrolysis of the water to release therefrom gaseous elements which permeate or are absorbed by the oil to render the same lighter and more mobile which facilitates its release from the sand and causes it to rise to the top of the water in the well. This results in a water body at the bottom of the well pocket upon which the electrode acts and produces electrolysis of the water.

Such water is frequently of a saline character and the gas produced by the electrolysis thereof releases chemicals of a caustic nature which cause a washing effect upon the sands and the removal therefrom of adhering oil. In the production of this gas salts are also liberated which collect to clog or close the water channels and by the pressure thus created break open new channels in the oil bearing sand to increase the production therefrom.

The method may be applied to ordinary equipment and during the usual pumping operation, and the electrically produced gases are absorbed by the oil and also collect in the higher strata to exert a pressure forcing the oil therefrom. An essential of the invention is not to effect electrolysis of the oil, but of the natural water in the well, and for that

reason the electric current is introduced at the lowest practical point therein so that the rising gases will be absorbed by the oil.

The invention has for an object to provide a new and improved method of recovering oil consisting in introducing into a well an electrode immersed in the water thereof, and feeding to said electrode an electric current of sufficient strength to release gaseous elements from the water by electrolysis.

A further object of the invention is to effect electrolysis of the mineralized water within an oil well to release therefrom salts which will collect and react upon the water channels of the well while exerting a pressure on the oil bearing sands thereof.

Another object of the invention is to utilize the saline or mineral waters of an oil bearing strata by an electrolysis of such water to produce a gas to be absorbed by the oil and exert a pressure thereon in the strata, and to further seal the water channels which results in a pressure opening new channels to the well hole thus releasing oil trapped in cavities or blocked by non-porous areas of the strata.

Other and further objects and advantages of the invention will be hereinafter set forth and the novel features thereof defined by the appended claims.

The drawing shows one application of the invention in which the well casing 10 extends downward to the usual pocket 11 and is sealed at its top 12. The tubing 13 is disposed within the casing and carries at its lower end the pump unit 14 from which a perforated casing 15 depends. Within this casing an electrode 16 is mounted by insulating blocks 17 and connected with a generator 18 by an insulated conductor 19. Desirable results have been secured by the use of a pure iron electrode and a current of approximately 50 amperes with an electromotive force of 2 volts. This low voltage and insulation from ground prevents heating and assures electrolysis of the saline liquid.

Such an electrical discharge causes electrolysis of the water at the bottom of the well, and the return current may be through the earth or a nearby well 20 provided with a duplicate electrode connected to the opposite

pole of the generator from the electrode first described. This causes the electrolytic action to continue in the water passages of the strata 21 intermediate the wells and the pressure re-
5 action upon the oil bearing sands thereof. If the water of a well be lacking in the minerals desired to produce the gaseous element by decomposition of the electrolyte proper chemicals may be introduced for that purpose.

10 In the application of the method the decomposition of the water by electrolysis liberates hydrogen and oxygen gases and also any mineral salts carried by the water. These gases are absorbed by the oil and react there-
15 on to facilitate its flow, while a pressure is generated within the sand or oil bearing strata causing a movement of the liquids toward the well hole. The presence of caustics produces a washing effect upon the oil sands 20 and the collection of the salt in the water channels close the same which results in a pressure causing the opening of new channels through the oil bearing sand. The method thus utilizes the water present in an oil well 25 to produce an aerating gas for the oil; pressure upon the sands; and chemical reaction of the liberated gases and mineral salts.

One apparatus for the application of the method has been shown and described, but 30 other means may be used for that purpose and the steps of the method varied without departing from the spirit of the invention as recited in the following claims.

What I claim, is:

35 1. The method of recovering oil consisting in introducing into a well an electrode insulated from ground and immersed in the water present in the well, and feeding to said electrode a current of sufficient strength to release 40 elements of the water by electrolysis.

2. The method of recovering oil consisting in introducing into a well an electrode insulated from ground and immersed in the water present in the well, feeding to said electrode a 45 current of sufficient strength to release gaseous elements of the water by electrolysis, and continuing the pumping of the well during such electrolysis.

3. The method of recovering oil consisting in introducing an electrode insulated from ground into the mineralized water of a well, and feeding to said electrode a current of sufficient strength to liberate the gases and mineral salts by decomposition of the water to 55 aerate the oil and create a pressure thereon while the salts are collected in the water channels.

4. The method of recovering oil consisting in introducing an electrode insulated from ground into the mineralized water of a well, and feeding to said electrode a current of sufficient strength to liberate a caustic element from the water to effect a washing ac- 60 tion upon the oil bearing sand.

65 5. The method of recovering oil consisting

in introducing an electrode insulated from ground into the saline water of a well, and feeding to said electrode a current of low voltage to effect electrolysis of the water to deposit solid matter within the water chan- 70 nels of the oil bearing strata.

6. The method of recovering oil, consisting in introducing a pumping unit into a well, disposing beneath said unit an electrode insulated therefrom and from ground, and sup- 75 plying to said electrode a current to effect electrolysis of the water at lower level in the well.

7. The method of recovering oil from adja- 80 cent wells consisting in disposing in each well an electrode insulated from ground and con- 85 nected to the opposite pole of a generator, and charging said electrodes with a direct current of low voltage to effect electrolysis within the water channels of the strata inter- 90 mediate said wells.

In testimony whereof I affix my signature.
